BLOOD TRANSFUSION DEVICE

John E. B. Swabacker, Chicago, Ill.

Application December 16, 1940, Serial No. 370,269

5 Claims. (Cl. 128—214)

This invention relates to a blood transfusion device in which a single container is used, and to a penetrable closure for the container having a guide member.

Among the objects of my invention is to provide a blood transfusion device in which a single container having a partial vacuum is used in combination with an insertable, withdrawal means having a valve control, to supply a single container for use in receiving, infusing, storing and dispensing in blood transfusions, to create a penetrable closure for the container, having a guide means visible from the outside of the container which will prevent broken or damaged needles, and such other objects, advantages and capabilities as will later more fully appear and which are inherently possessed by my invention.

While I have shown in the accompanying drawing a preferred form of my invention, yet I wish it understood that the same is susceptible of modification and change without departing from the spirit of my invention.

Referring to the drawing, Fig. 1 is a perspective view of my container; Fig. 2 is a detailed sectional view of the top of the container; Fig. 3 is a sectional view of the valve construction in combination with the container; Fig. 4 is an enlarged detailed view of my cap and stub; Fig. 5 is an enlarged detailed view of my stopper and Fig. 6 is an enlarged detailed perspective view of my removable closure member.

The embodiment selected to illustrate my invention comprises a container 10 having a hollow body portion 11 partially filled with an anti-coagulant solution such as a solution of sodium citrate 2½% in physiological solution of sodium chloride. There is a partial vacuum in the container 10, the open top 12 of which is sealed by a closure 13.

The closure 13 comprises a stopper 50 of rubber, composition or other suitable material. The stopper 50 has a lower central portion 51 adapted to enter the open top 12 of the container 10, and an upper portion 52 with flanges 53 resting on top of the walls of the open top of container 10.

A plate 15 of metal or other suitable material is positioned with its bottom portion positioned against upper portion 52 of stopper 50. A stub 17 is substantially centrally attached to plate 15. An opening 18 extends vertically through stub 17 and plate 15.

A removable member 20 of soft metal or the like has side portions with screw threads 54 to engage screw threads 55 on the side walls of the container 10 adjacent its open top 12. Remov-

able member 20 has a top portion 56 which bears down against the top of plate 15, and a cut-out portion 57 forming a grip 58 with a substantially central aperture 59. There are spaced scores 60 extending across top portion 56 and side portions 61 to aid in removal.

A washer 62 lies on plate 15 adjacent the bottom of stub 17. The outer walls of the stub 17 have screw threads 63 to removably receive the screw threads 64 of cap 65. Stub 17 extends upwardly through aperture 59 in removable member 20.

In cooperation with said container I provide a valve structure 21 of any suitable construction, but preferably that disclosed in my co-pending application, Serial Number 322,368, now Patent Number 2,226,538. Attached to the valve 21 is a needle 32. Also attached to valve 21 is a tube 26, on the other end of which is removably attached 20 a transfusion needle 34 adapted for insertion into the vein of a donor.

In the use of my blood transfusion device, my container 10 containing an anti-coagulant such as a solution of sodium citrate, 2½% in physiological sodium chloride solution, and having a partial vacuum sealed with a closure having a penetrable top, is available. With the valve in closed position I unscrew cap 65 from stub 17 and insert the valve needle 32 through opening 18 in stub 17 and stopper 50 into the container 10. The transfusion needle 34 is then inserted into the donor's vein and the valve 21 is slowly opened. The vacuum in the container by equalizing pressure causes the blood to flow from the transfusion needle 34 through the tubing 26 and valve structure 21 into the container 10. The solution in the container prevents coagulation of the blood. Swirling may be desirable.

The valve needle 32 may be withdrawn and 40 the container 10 sealed by screwing cap 65 into tight engagement with stub 17 and washer 62, thus forming a hermetic seal. The blood may then be refrigerated and stored or transported in the sealed container.

45 The same container 10 may then upon removal of cap 65, removable member 20, plate 15 and stopper 50 receive a suitable air providing dispensing cap or other dispensing apparatus and be placed in a dispensing position by turning the container 10 upside down and attaching its loop 36 to a suitable standard. The blood in the container 10 may then be passed through the dispensing cap or other dispensing apparatus to a suitable tube and dispensing needle to the recipient, as shown in my co-pending application Se-

rial Number 322,368, now Patent Number 2,226,538.

My container 10 is thus used throughout the withdrawal, storing, transporting and dispensing of the blood. There is no change from one container to another, to involve the problems of contamination, loss and extra apparatus.

I may also provide a removing member 66 adhering or otherwise attached to the upper surface 52 of the stopper 50. Said removing member 66 has a tab 67 on its outer edge. Said tab 67 is positioned to extend past the outer edge of plate 15 and is folded on top of plate 15 so as to be visible through cut-out portion 57 in removable member 20. The removing member 66 also has a central aperture 68 so as to not interfere with the passage of valve needle 32. When closure 13 is to be removed for the attachment of a dispensing cap, the user may by means of tab 67 quickly remove stopper 50 without danger of contamination to the open top 12 of container 10 by contact therewith.

In some instances my container with its penetrable closure may contain no partial vacuum, as the blood may be drawn in by virtue of gravity or venous pressure.

I may use a centrifuge blood to gather the blood, either with or without an anti-coagulant in it, to obtain serum or plasma as the case may be. After the blood has been centrifuged, that is, whirled at 2000 revolutions per minute for 20 minutes in the centrifuge, the cells sink to the bottom and the clear liquid stays on top. If there is anti-coagulant in the bottle this liquid is called plasma. This plasma may then be removed from the bottle by connecting a second empty gathering bottle thereto by plunging a long needle through the penetrable closure into the first bottle to the bottom level of the plasma. This needle is connected by means of tubing and a valve to the second bottle which is under high vacuum but which contains no anti-coagulant. It is then pulled over to the second bottle by means of a vacuum in the second bottle and is then pooled with other samples of plasma which may be in the second bottle.

Having thus described my invention, I claim:

1. A blood transfusion apparatus comprising a container having a desired amount of solution to prevent clotting of blood introduced therein, and a partial vacuum, a penetrable closure sealing said container, a guide member visibly positioned above said penetrable closure, said guide member having a guideway opening extending vertically therethrough, a tubing, a transfusion needle attached to one end of said tubing, a valve attached to the other end of said tubing, a hollow needle attached to said valve, said needle adapted to extend through said guideway in said guide member to then penetrate through said penetrable closure into said container so that upon the opening of said valve the vacuum in said container will cause blood to flow from the transfusion needle inserted into the veins of a donor into the container.

2. A blood transfusion apparatus comprising a container having a desired amount of solution to prevent clotting of blood introduced therein, and a partial vacuum, a penetrable closure sealing

said container, a guide member visibly positioned above said penetrable closure, said guide member having a guideway opening extending vertically therethrough, a cap removable attached to said guide member, a tubing, a transfusion needle attached to one end of said tubing, a valve attached to the other end of said tubing, a hollow needle attached to said valve, said needle adapted to extend through said guideway in said guide member to then penetrate through said penetrable closure into said container so that upon the opening of said valve the vacuum in said container will cause blood to flow from the transfusion needle inserted into the veins of a donor into the container.

3. A blood transfusion apparatus comprising a container having a desired amount of solution to prevent clotting of blood introduced therein, and a partial vacuum, a closure sealing said container, said closure comprising a penetrable stopper, a guide member plate supported on said penetrable stopper, a removable member holding the penetrable stopper and guide member plate in position on said container, said removable member having an aperture, a stub attached to said guide member plate and extending upwardly through the aperture in said removable member, said stub having a guideway opening extending vertically therethrough, a cap removably attached to said stub, a tubing, a transfusion needle attached to one end of said tubing, a valve attached to the other end of said tubing, a hollow needle attached to said valve, said needle adapted to extend through said guideway in said guide member and penetrable through said penetrable closure into said container so that upon the opening of said valve the vacuum in said container will cause blood to flow from the transfusion needle inserted into the veins of a donor into the container.

4. In combination with a container, a penetrable closure sealing said container, a guide member visibly positioned above said penetrable closure, said guide member having a guideway opening extending vertically therethrough, a cap removably attached to and sealing said guide member, the guideway opening of said guide member adapted to receive a needle inserted therein and to guide said needle therethrough to then penetrate through said penetrable closure into said container.

5. In combination with a container, a closure sealing said container, said closure comprising a penetrable stopper, a guide member plate supported on top of said penetrable stopper, a removable member holding said penetrable stopper and said guide member plate in position on said container, said removable member having an aperture, a stub attached to said guide member plate, said stub having walls extending upwardly through the aperture in said removable member, said stub having a guideway opening extending vertically therethrough, a cap removably attached to and sealing said stub, the guideway opening of said guide member adapted to receive a needle inserted therein and to guide said needle therethrough to then penetrate through said penetrable closure into said container.

JOHN E. B. SWABACKER.
